UNITED STATES PATENT OFFICE.

WILLIAM CRIGHTON, OF FORT WAYNE, INDIANA, ASSIGNOR TO THE KERR-MURRAY MANUFACTURING COMPANY, OF SAME PLACE.

CENTER-SEAL AND BY-PASS VALVE.

SPECIFICATION forming part of Letters Patent No. 449,578, dated March 31, 1891.

Application filed January 19, 1891. Serial No. 378,263. (No model.)

To all whom it may concern:

Be it known that I, WILLIAM CRIGHTON, a citizen of the United States, residing at Fort Wayne, in the county of Allen and State of Indiana, have invented certain new and useful Improvements in Center-Seal and By-Pass Valves; and I do hereby declare the following to be a full, clear, and exact description of the invention, such as will enable others skilled in the art to which it appertains to make and use the same.

This invention relates to a center-seal and by-pass valve adapted for connecting a series of gas-purifying boxes, from one to four or more, with a main gas-supply pipe and a main gas-discharge pipe and for circulating gas through a single box or through all of the boxes of the series, or through any two or three boxes in the series.

20 In conformity with the usual custom of setting four purifying-boxes in a plant I have constructed and arranged my center-seal and by-pass valve for connection with the inlet and outlet pipes of four purifying-boxes.

25 The principal object of my invention is to provide simple and effective means for simultaneously connecting four purifying-boxes in the circuit between the main supply and discharge pipes.

30 Another object is to provide for cutting out of the circuit either one, two, or three boxes, as desired, or for entirely closing the circuit between the supply and discharge pipes.

35 My improvement consists, mainly, in a peculiarly-constructed hollow valve-plug arranged centrally in the turning cap of the usual center-seal valve.

40 My improvement also consists in certain details of construction of such turning cap to adapt it for use with my central hollow valve-plug.

45 With the center-seal valve now generally in use but three purifying-boxes can be connected in the circuit at one time, and some one of the four boxes of the plant is necessarily idle all of the time, thereby causing a serious loss in the efficiency of the plant. By my improvements this difficulty is overcome, and any purifying-box after having been cleaned 50 and recharged can be brought back into the

circuit without cutting out of circuit any of the other boxes, as is the case with the old form of center-seal valve.

I will now describe my improved valve in detail with reference to the accompanying 55 drawings, in which—

Figure 1 represents a vertical section of the center-seal valve on line x x , Fig. 3. Fig. 2 represents a vertical section on the line y y through the upper part of the valve. Fig. 3 60 represents a horizontal section, on enlarged scale, through the turning cap and central plug. Fig. 4 represents a detached view in horizontal section of my central hollow plug.

The center seal is constructed of four principal parts—viz., the lower section F, the middle section G, the cap H, and the central plug I. The lower section F has arranged within it the usual central passage A, with which connects laterally the main supply-pipe A'. The usual annular chamber B surrounds passage A and has connecting with it laterally the main discharge-pipe B'. The section F also contains at the bottom the usual drip and seal chamber C, which in practice is supplied with a sealing-liquid for the lower ends of passage A and annular chamber B. It is also provided with openings at the bottom, closed by caps c c, for giving access to its interior. An overflow-pipe may 80 be connected to one of such openings when the cap is removed.

The middle section G of the valve is provided with concentric walls a b, forming extensions of the passage A and annular chamber B, and also with the usual radial partition-plates connecting the wall b with the outer wall of the chamber and dividing it into eight compartments or subdivisions, such as C' C², corresponding with the eight pipes 90 (four inlet and four outlet) which connect with the four purifying-boxes. Four inlet-pipes E' connect the four compartments C' with the four boxes, and four outlet-pipes E² connect said boxes with the four compartments C², all in the usual manner.

The turning cap H of my center-seal valve is of special and improved construction to adapt it for use with my new central hollow plug I. The cap is provided with a central 100

opening adapted to receive a preferably tapering plug I, and at the bottom is provided with a circular or segmental floor K, inclosing about seven-eighths of the circumference of the central opening between the radial partition h' and h^8 , and of sufficient width to cover the annular chamber B in the middle section G. A segmental space M, equal to one-eighth of the circumference around the central opening and over the annular chamber B, is left open between the radial partition-plates h' and h^8 for the escape of gas from any purifying-box with which it happens to be in connection to the main discharge-pipe.

15 The cap II is divided into eight compartments by the vertical radial partition-plates h' , h^2 , h^3 , h^4 , h^5 , h^6 , h^7 , and h^8 , extending from the outer circumferential wall to the inner edge of the floor K and forming at their inner edges a support for the central valve-plug I. The short space between the inner ends of the partition-plates h' h^8 is closed by a vertical wall L, extending from the top to the bottom of the cap and forming a partition between one of the compartments II^2 in the cap and its central opening containing the plug for directing gas down into the annular outlet-chamber B below the floor K. The radial partition-plates h' to h^8 , inclusive, correspond to the radial partitions in the middle section G and divide the cap up into compartments II' II^2 , corresponding to the compartments C' C^2 in such middle section G. In practical use an outlet-chamber II' of the cap is always arranged directly above an outlet-chamber C' of the middle section G.

The abutting edges of the walls and partition-plates, both in section G and in cap II, are planed smooth, so as to make tight joints 40 and permit the cap to be readily rotated upon section G. The cap II may be rotated by any of the well-known mechanism adapted to the purpose, and the plug I may be independently rotated within the cap by means of a wrench applied to the squared projection i in the top plate m.

My central hollow plug I is arranged in the cap II directly above and in communication with the central passage A of the valve. It is closed at the top by a plate m, provided with flanges which overlap the top plate II and is open at the bottom. The plug I is preferably formed with four walls o' , o^2 , o^3 , and o^4 , all joining at the bottom with the annular rim n, and also joining laterally with the vertical circumferential posts p p' p'' p''' , which join the lower rim n with the top plate m. The walls o' o^2 o^3 are formed re-entrant or concave, as shown in Figs. 3 and 4, so as to form by-pass recesses N' N'' N''' for the passage of gas between the different compartments II' and II^2 of the cap. The wall o^4 is of concave form and is flush with the outer circumference of the plug, being adapted to fit the wall L between the inner ends of the partition-plates h' and h^8 , as shown in Fig. 3. The re-entrant walls o' o^2 o^3 span the spaces

between the alternate partition-plates, as h^2 h^4 , between h^4 and h^6 , and between h^6 and h^8 . Between the ports p p' , &c., I preferably provide the strengthening-posts n' , which extend from the lower rim n to the top plate m, and such posts n' register with alternate partition-plates, as h^3 h^5 , &c. The annular rim n at the bottom fits within the circular floor K, as shown in Fig. 1. The wall o^4 and the circumferential posts of the plug are preferably inclined downward and inward, so that the plug may be more readily lifted out of its seat when desired.

Fig. 3 represents the cap and plug in proper position for connecting four purifying-boxes in the circuit between the main supply and discharge pipes. By turning the plug one-fourth revolution to the right one box will be 70 cut out and three remain in the circuit. One-fourth additional turn to the right cuts out another box, leaving but two in the circuit, and one-fourth additional turn to the right leaves but one box in the circuit. The convex wall o^4 of the plug is provided with an opening o for forming a passage between the interior of the plug and any one of the inlet-chambers II' in the cap. Should it be desired to shut off the flow of gas to all of the purifying-boxes, the valve-plug I is turned one-eighth revolution to the left from the position shown in Fig. 3, so that opening o will be covered by the segmental wall L, connecting the inner ends of the partitions h' h^8 .

When operating with four boxes for purifying gas, and it is desired to remove the fouled purifying material from one of the boxes, the plug is first turned one-fourth revolution to the right from the position shown in Fig. 3 to throw box No. 1 out of the circuit. During the short period of cleaning and recharging box No. 1 but three boxes connect in the circuit and are in use for purifying gas; but as soon as box No. 1 has been recharged it will be brought back as the last box of the circuit by turning cap II one-fourth revolution to the right and then turning the plug back one-fourth revolution to its first relative position in the cap. The gas will now first enter box No. 2, and then pass successively through boxes No. 3, No. 4, and lastly through box No. 1. In order to clean and recharge the succeeding boxes, the same procedure is followed—viz., first turning the plug one-fourth revolution to the right to throw out of circuit the fouled box, and then, after cleaning and recharging such box, turning the cap one-fourth revolution to the right and the plug back one-fourth revolution to the left to its previous relative position in the cap, thus bringing the recharged box back as the last in the circuit. This form of cap and plug is simple in construction and operation and quite effective in practical use.

When the cap and plug are set for connecting four boxes in the circuit, as shown in Fig. 3, the gas flows from the main supply-pipe A' up the central passage A, through the

hollow plug I, and through its side opening o into compartment II', thence down through the corresponding compartment C' in section G, thence down through pipe E' to box No. 1, and returns from such box through pipe E² up into the compartment H² of the cap. Now, in order to pass into box No. 2, the gas first passes from compartment H² through the by-pass recess N in the plug into the compartment H' of the cap, from which it passes, as before explained, into box No. 2 and back into another compartment H² of the cap, from which it passes through the second by-pass recess N' in the plug in order to reach box No. 3. The gas on returning from box No. 3 into compartment H² passes through the third by-pass recess N'' in the plug and thence out of box No. 4, on returning from which it passes from the last compartment H² of the cap through the segmental opening M in floor K down into the annular chamber B, and thence escapes by the main discharge-pipe B'. With the plug standing in the cap, as shown in Fig. 3, the gas can be made to enter first any one of the four boxes by turning the cap H into the proper position, and by turning the plug around within the cap either one, two, or three of the boxes may be cut out of the circuit.

I do not broadly claim herein the valve chamber or cap divided into compartments and containing a plug-valve having an opening in its wall to direct the flow of gas into the compartments of the cap; nor do I herein broadly claim such valve chamber or cap containing a plug-valve provided with inlet and outlet openings and with a recess in its walls serving as a by-pass for gas between compartments of the cap, as such construction is made the subject of a separate application bearing Serial No. 356,853, filed June 26, 1890.

Having described my invention, what I claim, and desire to secure by Letters Patent, is—

1. In a center-seal valve, a turning cap divided by radial partitions into suitable compartments and provided with a central hollow plug provided with an opening in its wall connecting its interior with one of the compartments of the cap, and also provided with

by-pass recesses for connecting inlet and outlet compartments of the cap in pairs or sets of two, substantially as described.

2. In a center seal for gas-purifying boxes, the turning-cap section provided with a central opening containing a hollow plug and also provided with radial partitions extending from said hollow plug to its outer wall and dividing it into suitable inlet and outlet compartments, said hollow plug having an opening in its side wall forming a passage from its interior into a compartment of the cap and also having two or more by-pass recesses in its wall connecting adjacent inlet and outlet compartments of the cap in pairs or sets of two, substantially as described. 55

3. The cap-section divided by radial partitions into inlet and outlet compartments and having a central vertical opening, in combination with a hollow plug seated in said central opening and having three re-entrant walls connecting with three circumferential posts arranged to register with alternate radial partition-plates of the cap and forming by-pass recesses connecting adjacent inlet and outlet 70 compartments, said plug also having an opening in its side wall for the passage of gas from its interior into the inlet-compartments of the cap, substantially as described. 75

4. In a center seal for gas-purifying boxes, the combination of the gas-inlet pipe with the valve-chamber located above the same and divided by suitable partition-walls to direct the flow of gas and containing a hollow plug connecting directly with the inlet-pipe, said 80 plug having four walls, one of which fits snugly within the inner wall of the valve-chamber and having an opening to direct the flow of gas into the compartments of the valve-chamber and the others formed re-entrant 85 and each of a width equal to the distance between alternate partitions of the valve-chamber, whereby one or all of the series of boxes can be put into operation. 90

In testimony whereof I affix my signature in presence of two witnesses.

WM. CRIGHTON.
